CLAIM

The ornamental design for a drawer cart with shelf, as shown and described.

DESCRIPTION

FIG. 1 is a front perspective view of a first embodiment of a drawer cart with shelf, showing my new design.

FIG. 2 is a left side perspective view of the drawer cart with shelf of FIG. 1;

FIG. 3 is a rear perspective view of the drawer cart with shelf of FIG. 1.

FIG. 4 is a right side perspective view of the drawer cart with shelf of FIG. 1.

FIG. 5 is a top perspective view of the drawer cart with shelf of FIG. 1.

FIG. 6 is a bottom perspective view of the drawer cart with shelf of FIG. 1.

FIG. 7 is a front perspective view of a second embodiment of a drawer cart with shelf, showing my new design.

FIG. 8 is a left side perspective view of the drawer cart with shelf of FIG. 7.

FIG. 9 is a rear perspective view of the drawer cart with shelf of FIG. 7.

FIG. 10 is a right side perspective view of the drawer cart with shelf of FIG. 7.

FIG. 11 is a top perspective view of the drawer cart with shelf of FIG. 7; and,

FIG. 12 is a bottom perspective view of the drawer cart with shelf of FIG. 7.

The broken lines in the figures depict portions of the article that form no part of the claimed design.

1 Claim, 12 Drawing Sheets
